PARTITION

David M. Moore, Pittsburgh, Pa., assignor to Armstrong
Store Fixtures Company, Pittsburgh, Pa., a corporation of Pennsylvania

Filed May 23, 1968, Ser. No. 12,058

Term of patent 14 years

Int. Cl. D25—01

U.S. Cl. D28—1

FIG. 1 is a front perspective view of a partition showing my new design;

FIG. 2 is a rear perspective view of the partition, showing the rear surfaces not seen in FIG. 1;

FIG. 3 is a front perspective view of a modified form of partition shown in FIG. 1; and

FIG. 4 is a rear perspective view of the modified form of partition, showing the rear surfaces not seen in FIG. 3.

I claim:

The ornamental design for a partition, as shown.
